UNITED STATES PATENT OFFICE.

FRANCIS W. BYRNE, OF CONNELLSVILLE, PENNSYLVANIA.

COAL LOADER.

Application filed September 27, 1921. Serial No. 503,539.

To all whom it may concern:

Be it known that I, FRANCIS W. BYRNE, a citizen of the United States, and a resident of Connellsville, in the county of Fayette and State of Pennsylvania, have invented certain new and useful Improvements in Coal Loaders, of which the following is a specification.

My invention relates to improvements in loaders, more especially for the purpose of loading newly loosened coal in a mine on a car, and it consists in the constructions, combinations and mode of operation herein described and claimed.

One of the foremost objects of the invention is to provide a mechanical shovel which gathers a load on a forward stroke and automatically dumps the load on a rearward stroke, onto an arrangement of belts which 20 convey the material to a car.

A further object of the invention is to provide means by which the shovel may be projected as far as desired, raised, lowered, or returned when desired, extended into corners, and in fact manipulate the shovel in any manner to meet any particular conditions likely to occur in a loading operation.

Other objects and advantages will appear 30 in the following specification, reference being had to the accompanying drawings, in which:—

Figure 1 is a longitudinal section (parts in elevation) of the preferred form of loader,

Figure 2 is a side elevation (parts in section) of the first modification of the mechanical shovel,

Figure 3 is a plan view of the arrangement in Figure 2,

Figure 4 is a detail side elevation (somewhat enlarged) showing the shovel in Fig. 2 in the dumping position,

Figure 5 is a detail section taken substantially on the line 5—5 of Figure 3,

Figure 6 is a section on the line 6—6 of Figure 3,

Figure 7 is a front elevation of the loader, the longitudinal conveyor being shown in section for the purpose of illustrating its construction,

Figure 8 is a vertical section taken substantially on the line 8—8 of Figure 2, the shovel-operating motor being shown in elevation,

Figure 9 is a detail cross section taken on the line 9—9 of Figure 2,

Figure 10 is a diagram illustrating the relationship of the loading machine to a train of cars when in operation in the lead 60 of a mine,

Figure 11 is a detail cross section on the line 11—11 of Figure 1, and

Figure 12 is a longitudinal section of a second modification of the loader, wherein 65 the shovel is operated pneumatically.

Attention is directed to Figure 1 which illustrates one form of the coal loader. The loader is primarily intended to be used in a coal mine, although it may obviously be 70 used for shoveling any kind of solid material.

The track 1 is laid in the lead 2 of a mine (Figs. 2 and 10) and extended inwardly or forwardly as the length of the lead increases by loosening and removing the coal at the head. The wheels 3 of the truck 4 run on the track and the truck, which is the foundation on which the loader is built, may be moved into position on the track, either by means of its own motive power or it may be pushed into place and there fixed by suitable brake means.

A turntable 5 has sides 6 terminating in bearings for supporting the trunnions 7 of 85 the carriage 8. The latter carries the compound shovel beam, composed of the members 9 and 10, respectively with racks 11 and 12 on the under side.

The upper beam, which is the longest of 90 the two members, ends in the bifurcated head 13 in which the shovel 14 is mounted on trunnions 15. Gears 16 and 17 mesh with the racks 11 and 12. The first gear is of a greater diameter than the second. The 95 result of revolving the shaft 18 (which carries the gears mentioned) through the gear train 19, 20, 21 and 22, is to project the long beam 9 faster than the short beam 10, thus gaining the advantages of speed of 100 shovel projection and length of projection without sagging of the compound beam, for it is to be observed that the lower beam serves as a support for the upper beam.

A rheostat 23 controls the motor 24 which 105 carries the pinion 19 of the gear train mentioned above. Current is furnished by the generator G. The direction of rotation of the motor shaft is controlled by the reversing switch 25. When the switch is in one posi- 110

tion, the motor shaft is made to turn in a counter clockwise direction and thus project the shovel 14 into the load. Conversely, when the switch is reversed to cause the 5 motor shaft to revolve in a clockwise direction, the shovel is withdrawn with the load.

Dumping of the load occurs when the latch trip 26 strikes the abutment 27. The 10 rocking of the intermediate bell crank and link connections moves the latch 28 from the lug 29 so that the front part of the shovel 14 rocks on the trunnions 15 by virtue of the weight of the load on the rear end, causing the load to discharge onto the cross conveyor 30 (Fig. 4). The cross conveyor carries the coal to the longitudinal conveyor 31, which in turn carries it rearwardly to discharge in any one of the train of cars 32 as shown in Figure 10.

20 Power for the driving of the transverse conveyor 30 is derived from the turntable shifting motor 33 by means disclosed in Figure 2. Said means comprises the transmission case 34, directly driven shaft 35, 25 sprockets 36 and driving chain 37 (Fig. 7). The longitudinal conveyor 31 is driven by a suitable motor (not shown) which is wholly independent of the other motors. In other words, the longitudinal conveyor 31 may be 30 moved wherever desired, without shifting the position of the loader.

A motor 38 drives a shaft 39 (Fig. 1) which carries a loose worm pinion 40 for raising and lowering the carriage 8. It 35 also carries a loose worm pinion 41 which meshes with the worm sector 42, and is for the purpose of revolving the turntable 6 within prescribed limits. The object in thus revolving the turntable is to direct the shovel 14 toward the corners of the lead 2. The object in raising and lowering the carriage 8 is to direct the shovel into the material and retain its load when filled.

40 A rheostat 43 controls the speed of the motor 38. The direction of rotation of the shaft 39 is governed by the reversing switch 44. The generator G furnishes current. The worm pinion 40 meshes with a worm gear 45 on a shaft 46 which carries a worm 45 pinion 47 in engagement with the quadrant 48. The quadrant is fixed on the carriage 8. The proper positioning of the rheostat 43 and switch 44, and the closure of the clutch 49, results in swinging the carriage 8 into 50 the position shown in Figure 1 (for example) so that the shovel 14 assumes a position in readiness to enter the pile of material.

The proper positioning of the rheostat 23 and switch 25 results in projecting the shovel 55 14 into the material, as described above. Both switches 25 and 44 should be reversed when the shovel is full. This causes the return of the compound shovel beam 9, 10, and the elevation of the shovel. As soon as the 60 latch trip 26 strikes the abutment 27, (dump-

ing the load) both switches 25 and 44 should again be reversed, repeating the foregoing operation.

A clutch 50 controls the operation of the worm pinion 41. When the latter is made 70 to turn, a movement of the turntable 6 in respect to the sector 42, results. The sector is fixed, being integral with the shaft 51 which serves as the pivot for the turntable. A ball race 52 provides an adequate bearing 75 for the turntable and its carried parts.

Provision is made for getting the shovel 14 more nearly in line with a corner of the lead. There may be instances when the mere turning of the turntable 6 in order to direct 80 the shovel 14 into a corner, would be insufficient because of the inability to completely shovel up the material from an angle. In such an event, the entire mechanism from the turntable up, is moved laterally in respect to the truck 4. Figure 2 shows how 85 this is done.

A slide 53 constitutes the base in which the shaft 51 is fixed by means of a key (Fig. 6). This slide has lateral tongues which 90 occupy grooves 54 running crosswise of the truck 4. Racks 55 and 56 beneath the slide, enable moving the latter toward the left and right respectively (looking forwardly).

When the pinion 57 is clutched to the 95 shaft 35, the slide 53 is made to move toward the left, following the direction of the cross conveyor 30. When the gear 58 is clutched to the shaft 35, the reverse motion of the slide results. The gear 58 meshes with a 100 gear 59 (Fig. 9) on a countershaft 60 which carries a gear 61 (Fig. 2) in turn engaging the rack 56. It is by the means last described that the whole apparatus from the slide 53 up, is capable of being moved laterally on the truck 4, without changing the 105 position of the latter.

The modification in Figure 2 differs mainly from the loader in Figure 1, by the absence of a compound shovel beam and by 110 a difference in the arrangement of the means for raising and lowering the shovel and swinging the turntable. Like reference numerals, but with the exponents "a," are used to designate like parts appearing in Figure 1 and not referred to in connection with the description of that figure. The shovel-operating motor 24^a drives a counter shaft 62 continuously, through the gear train 19^a, 20^a, 63, 21^a, and 22^a. The gears 19^a and 20^a are on the far side, while the gears 63, 21^a and 22^a are on the side nearest the observer 115 in Figure 5. The countershaft 62 carries a gear 64 on the far side, precisely like the gear 22^a, and it is the gear 64 which meshes with a pinion 65 on the crank shaft 66. The turning of the crank shaft lowers and raises the shovel 14^a by rocking the carriage 8^a on its bearings 7^a.

120 Cranks 67 (Figs. 3, 5 and 6) have link 130

connections 68 to ears 69 on the carriage 8^a. A clutch 70 (when shifted) secures the pinion 65 on the crank shaft 66 so as to rock the carriage 8^a and raise or lower the shovel 14^a, depending on the direction of rotation of the shaft of the shovel operating motor 24^a. A brake 71 of any suitable type and carried by the shaft 66, is intended to hold the shaft when it has revolved 180° from the 10 position in Figure 5, at which time the shovel is elevated and the clutch 70 is disconnected from the pinion 65, preparatory to the reversal of the motor 24^a.

The direction of rotation of the motor is 15 controlled by a reversing switch 25^a (Fig. 2) and the speed is controlled by the rheostat 23^a. When the switch 25^a is in one position, the motor shaft turns in a counter clockwise direction, causing the projection 20 of the shovel beam 9^a so that the shovel enters the material. Motion for the projection of the shovel is transmitted from the motor 24^a through the pinion 19^a, gear 20^a, pinion 63, gear 21^a, pinion 72 (Fig. 8) and the gears 25 73 and 74 which are carried by the rack shaft 75, in turn mounted in bearings 76 beneath a frame part of the carriage 8^a.

The pinion 72 (Fig. 8) is made integral with the gear 21^a and both are loose on the 30 trunnion 7^a which, with its companion trunnion, rocks in bearings on the turntable sides 6^a. The gear 74 meshes with the rack 11^a and when the motor shaft revolves in the counter clockwise direction, as stated 35 above, the beam 9^a is projected.

As the shovel enters the material and approaches what the operator may regard as a sufficiently long stroke, the clutch 70 is thrown in so that the shovel is raised from the material with its load. The brake 71 is then applied and the switch 25^a is reversed so as to cause the motor shaft (motor 24^a) to revolve in the clockwise direction and return the shovel beam 9^a. The parts soon assume the position illustrated in Figure 4.

As soon as the trip 26^a engages an abutment on the carriage 8^a, the latch 28^a is displaced from the lug 29^a so that the front part of the shovel 14^a swings downwardly 50 and rearwardly on the pivot 15^a to discharge the material on the cross conveyor 30^a. The switch 25^a is opened when the retracted position of the shovel (Fig. 4) is reached, and as soon as the load is discharged, the brake 55 71 is released to permit the shovel and beam to assume the original position. Figure 2 illustrates this position, but here the shovel and beam are partly projected, the switch 25^a having been thrown into the forward 60 position.

Rollers 77 on the carriage 8^a, furnish bearing support for the projectable shovel beam 9^a. The latter has lateral flanges 78 (Fig. 8) which bear on the rollers. The 65 lowermost roller on the right side of the

carriage (Fig. 4) furnishes the abutment (mentioned above) for the latch trip 26^a.

A provision similar to that in Figure 1 is made for the partial revolution of the turntable 5^a in Figure 2. - The worm 41^a (Fig. 6) meshes with the sector 42^a, and when the clutch 50^a is thrown in, the shaft 39^a is driven from the counter shaft 62 through the gears 79 and 80.

The shovel 14^a consists of two parts, 75 namely, the front part which moves on the pivot 15^a, and the back part 81^a which has its main support between the adjusting yoke 82^a and the links 83^a. The latter are connected between the parts 14^a and 81^a, an additional purpose of the links being to limit the downward swinging of the rear end of the front part 14^a, arrow a, (Fig. 4), so that the material may not spill over the exposed right side of the cross conveyor 30^a as it is 85 discharged from the shovel.

A hand wheel 84 enables adjustments of the shovel on the pivot 15^a, so that the leading edge may be raised or lowered. The hand wheel 84 works on a screw shaft 85 90 which extends upwardly from the yoke 82, through a bearing 86 on the beam head 13^a.

The modification in Figure 12 illustrates how the shovel may be operated by fluid pressure. Instead of using a beam and rack 95 for the support and projection of the shovel, the latter is now carried by the rod 87 which has a piston 88 on the rear end. The piston moves in the inner cylinder 89. This cylinder has a piston head 90 at the rear end, 100 which latter moves in the outer cylinder 91.

The piston head 90 does not advance in its cylinder 91 until the piston 88 has advanced to the limit of its stroke in the inner cylinder 89. The operation of projecting 105 the shovel is like this: The valve 92 is turned to the position illustrated in Figure 12, so that fluid under pressure from a suitable reservoir enters the inner cylinder 89 by way of the pipe 93 and port 94. The left 110 end of this port is covered by the rear wall of the piston head 90, so that at this time, no fluid can get behind the head 90.

Fluid having entered the inner cylinder 89, forces the piston 88 forwardly until the latter strikes the front end of the inner cylinder 89 with sufficient force to cause the rear wall of the head 90 to uncover the left end of the port 94. Pressure fluid continuing to enter, now occupies the space behind 115 the head 90, driving the latter forwardly. The forward extension of either the rod 87 or inner cylinder 89, may stop where the operator desires, and obviously if the pile of material is near enough for the shovel to 120 reach it by the projection of the rod 87, the inner cylinder 89 will not come into play as a further projector for the shovel.

Fluid ahead of the piston 88 escapes into the outer cylinder 91 through the port 95 at 125 130

the front end of the cylinder 89. The outer cylinder has a port 96 through which the fluid in turn exhausts to the valve. The exhaust ports 95 and 96 become fluid inlet ports when the valve 92 is reversed and on the other hand, the port 94 and pipe 93 will become the means for conducting fluid out of the cylinders when the pistons 88 and 90 move to the left.

10 Suitable packing boxes 97 and 98 at the ends of the cylinders 89 and 91 respectively, insure tight joints for the moving parts. They also act as supports for the moving parts within them. In its other respects, 15 the loader in Figure 12 may be constructed and operated precisely like the loader either in Figures 1 and 2, and therefore the description of either of the latter, will suffice for the remaining mechanism in Figure 12, 20 of which description is omitted.

While the construction and arrangement of the improved loader as herein described and claimed is that of a generally preferred form, obviously modifications and changes 25 may be made without departing from the spirit of the invention or the scope of the claims.

I claim:

1. A loader comprising a carriage, a table 30 having bearings for supporting trunnions on the carriage, mechanism on the table for actuating a shovel beam which is reciprocable in the carriage, and means on the carriage for driving said mechanism through 35 a gear on the axis of the trunnions to either reciprocate the beam or rock the carriage on its trunnions.

2. A loader comprising a table supporting 40 a carriage in which a shovel beam is reciprocable, a source of motive power carried by the carriage adapted to function to reciprocate the beam in the carriage, rock the carriage on the table and turn the table; and means causing the performance of said functions either singly or in combination.

3. A loader comprising a truck to be moved into a lead, guides arranged transversely of the truck, a slide which carries a shovel and its operating mechanism, supported by the guides; and rack and gear devices for shifting the slide on the guides so that the shovel may be pointed directly into the corners of the lead.

4. A loader comprising a table provided 55 with trunnion bearings, a carriage having trunnions supported in said bearings, turnable means mounted on the table, and means by which the turnable means and the carriage are connected to rock the latter on the trunnions upon operation of the turnable means.

5. A loader comprising a table having a pair of sides provided with trunnion bearings, a carriage situated in the space between 60 the sides, means forming trunnions by which

the carriage is supported in said bearings, turnable means carried by the table, and means providing an operating but movable connection between the carriage and said turnable means adapted to rock the carriage on its trunnions upon operation of said turnable means.

6. A loader comprising a table having sides provided with trunnion bearings, a carriage having means to form trunnions 75 mounted in said bearing permitting a rocking motion of the carriage, a motor mounted on the carriage, a countershaft located on the table between the sides, gear connections by which the countershaft is driven from 80 the motor, a crank shaft mounted on the table between the sides, connections between the carriage and the cranks of said shafts adapted to rock the carriage upon operation of the crank shaft, a loose pinion on the 85 crank shaft in mesh with one of the aforesaid gear connections carried by the countershaft, and a clutch on the crank shaft for fastening the loose gear at will.

7. A loader comprising a table having 90 trunnion bearings, a carriage having means providing trunnions by which the carriage is mounted on said bearings, a shaft upon which the table is mounted to swing, a gear sector carried by said shaft 95 a motor on the carriage, a counter shaft on the table, driving connections between the countershaft and motor by which the former is rotated, a shaft on each side of the countershaft, means for driving one 100 shaft from the countershaft, means for then rocking said carriage through said driven shaft, means for driving the other shaft from the countershaft, and means in connection with the gear sector then causing the 105 table and all of its carried parts to turn upon the sector shaft.

8. A loader comprising a carriage, means on the carrier forming trunnions, a table having bearings for supporting the trunnions, a shovel beam which is reciprocable in the carriage, means carried by the carriage to reciprocate the beam, means carried by both the table and carriage to rock the carriage on its trunnions, means carried by the 110 carriage from which driving power is derived, and means which has a loose mounting on one of the trunnions for transmitting the driving power to either the reciprocating or rocking means.

9. A loader comprising a carriage, means on the carriage forming trunnions, a table having bearings for supporting the trunnions, a shovel beam reciprocably mounted on the carriage, a rack carried by the beam, 115 rack gears mounted on the carriage, crank shafts mounted on the table, links connecting the cranks with the carriage, a counter shaft mounted on the table, gear connections between the two shafts adapted to turn the 120 125 130

- crank shaft and thereby rock the carriage on its trunnions, a driving motor carried by the carriage, and a double gear for transmitting the driving power from said motor to one of the rack gears and to the gear connections of said countershaft, said double gear being loose on one of the trunnions, the rotation thereof therefore not interfering with the aforesaid rocking movement.
10. A loader comprising a carriage, trunnions on the carriage, bearing means in which the trunnions are supported for rocking movement, a shovel beam, rollers on the carriage by which the shovel beam is supported, a rack on the shovel beam, a rack shaft supported by the carriage, a driving gear carried by the shaft in mesh with the rack to reciprocate the shovel beam, a driven gear carried by said shaft, a motor on the carriage, and a gear loose on one of the trunnions and driven by the motor the driven gear on the rack shaft meshing with said gear and having a planetary motion in respect thereto when the carriage rocks.
15. A loader comprising a carriage, a shovel beam having upper and lower side flanges and a connecting bridge, rollers mounted on the carriage with which the lower flanges engage for support, others of which rollers engage the upper flanges to keep the beam in place, a rack mounted on the connecting bridge, a rack shaft journaled on the carriage, and a gear on the shaft in mesh with the rack adapted to reciprocate the beam.
20. A loader comprising a truck having grooves formed therein, a slide having tongues which occupy the grooves, a table mounted on the slide, a shovel and its appurtenances carried by the table, and means for moving the slide in respect to the truck.
25. A loader comprising a truck adapted to run on tracks, a slide having tongues occupying grooves which extend laterally of the truck, a shaft fixed in the slide, a table pivoted on the shaft, bearings between the table and slide permitting a turning motion, a gear sector fixed on the shaft and being adapted to hold the table down, a carriage mounted on the table, a shovel beam carried by the carriage, means cooperating with the gear sector causing the table to turn on the slide for the adjustment of the shovel beam in radial directions, and means to move the slide laterally of the truck carrying the table and all appurtenances therewith to permit approaching corners with the shovel in directions other than radial.
30. A loader comprising a truck, a driven shaft carried by the truck, a slide mounted to move on the truck, a pair of racks carried by the slide, a trunnion for each rack,
35. a countershaft by which one of the pinions is carried, means for clutching the countershaft to the driven shaft to move the slide in one direction in respect to the truck, and means for clutching the other pinion to the driven shaft for moving the slide in the opposite direction.
40. A loader comprising a truck, a conveyor mounted to operate across the front of the truck, a driven shaft disposed longitudinally of the truck, means by which one end of the conveyor is driven from the shaft, a beam having a shovel, means by which it is supported on the truck, and means carried by said supporting means operable independently of the driven shaft and adapted to reciprocate the beam across the conveyor.
45. A loader comprising a truck, a conveyor mounted to operate across the front of the truck, a shaft disposed longitudinally of the truck, a motor and transmission mechanism by which it is driven continuously, means by which the conveyor is driven continuously from the shaft, a slide mounted to move transversely of the truck, means by which the slide may be moved in either lateral direction from the driven shaft, a beam having a shovel, means by which the beam is supported on the slide, a driving motor carried by said supporting means, and means transmitting the power of said motor to the beam to drive the shovel out and back to discharge upon said conveyor.
50. A loader comprising a truck, a conveyor mounted to operate across the front of the truck, a shaft disposed longitudinally of the truck, a motor and transmission mechanism by which it is driven continuously, means by which the conveyor is driven continuously from the shaft, a slide mounted to move transversely of the truck, means by which the slide may be moved in either lateral direction from the driven shaft, a beam having a shovel, means by which the beam is supported on the slide, a driving motor carried by said supporting means, means transmitting the power of said motor to the beam to drive the shovel out and back to discharge upon said conveyor, and means carried by the shovel adapted to engage a part of said supporting means to fit the shovel for dumping upon the conveyor.
55. The combination in a device of the character described of a truck, a slide movable upon the truck, a table situated above the slide and truck, a shaft carried by the slide and passing through the table, and means including a gear sector carried upon the upper extremity of the shaft to hold the table down.

FRANCIS W. BYRNE.
